UNITED STATES PATENT OFFICE.

EDMUND WEIGELE, OF BERGENFIELD, NEW JERSEY, ASSIGNOR TO G. & G. ATLAS SYSTEMS, INC., OF NEW YORK, N. Y., A CORPORATION OF NEW YORK.

CENTRAL STATION APPARATUS FOR PNEUMATIC DISPATCH SYSTEMS.

Application filed September 1, 1926. Serial No. 132,926.

This invention relates to a central station installation for pneumatic dispatch systems. In Letters Patent No. 1,576,312, granted March 9, 1926, there is described and claimed 5 a pneumatic dispatch central station installation characterized by a relatively high degree of flexibility of operation to provide for the rapid addition to or subtraction from the number of operators at the cashiers' station 10 in accordance with the demands of the work. This advantageous feature of the installation was achieved by the provision of a carrier relay station in adjacent and supervising relation to the cashiers' station, the operator 15 at the relay station relaying received carriers to the cashiers as the work required.

A general object of the present invention is to provide a central station installation of the general type described and claimed in 20 the patent referred to, in which, in addition, special provision is made for satisfying emergency conditions in a portion of the system, such as the occurrence of a special sale in a single department of a department 25 store.

The invention comprises a central dispatch installation in which provision is made, as in the prior apparatus referred to, for relaying incoming carriers to a cashiers' 30 station in the normal course of the work, and in which provision is also made for diverting arriving carriers from any desired number of the incoming tubes directly to specially provided operators' stations and without sub- 35 jecting the carriers so treated to the intermediate relay dispatch operation.

A feature of the invention resides in the provision of troughs or ways distributed at the central station to receive carriers from 40 the incoming tubes and to deliver the received carriers to the relay station, the delivery ends of the incoming tubes being provided with means for diverting the arriving carriers from the troughs or ways directly to 45 emergency operators' stations provided for the purpose adjacent to the delivery ends of the tubes.

Other features of the invention will be hereinafter described and claimed.

50 In the drawings, in which a preferred embodiment of the invention has been selected for illustration:

Figure 1 is a diagrammatic view in plan of a central dispatch installation embodying 55 the invention;

Figure 2 is a view taken in side elevation and partly in vertical section on the line 2-2 of Figure 1;

Figure 3 is a view in end elevation and in vertical section taken on the line 3-3 of 60 Figure 1;

Figure 4 is a view in front elevation of the parts shown in Figure 1.

Referring to the drawings for a more detailed description of the invention, a central 65 station installation for a pneumatic dispatch system is shown in which a combined relay and dispatch operators' station is shown at 5, to which carriers are delivered from the discharge terminals of incoming tubes 6 by 70 way of inclined troughs or chutes 7 and 8. The various chutes converge at a carrier receiving receptacle 9 to which access is had by the operator at station 5. At 10 is shown a cashiers' station to which carriers are 75 relayed or redispached by the operators' station 5 and through the agency of carrier tubes 11 having their inlet ends 12 located at points adjacent to the operators' station 5. The carriers thus distributed among the op- 80 erators at station 10 are treated by those operators, the change being made and the record slip indicating the transaction, where- 85 upon the carriers are returned by the operators at station 10 by way of the tube lines 13 to the carrier receiving receptacle 14 at station 5 from which carriers are redispached through the dispatch tubes 15 to the out- 90 lying stations from which the carriers were originally dispached. This construction 90 and arrangement of apparatus follows in general the construction referred to in the prior patent.

A feature of the present invention is the provision for special or emergency treatment of carriers arriving from a section or department of the system wherein special activity is taking place, such as a sale in one or more departments of a store. In such a case it is desirable that the step of 100 relaying the carriers from the dispatchers' station 5 to the operators' station 10 be done away with. This rearrangement expedites the handling of the carriers by causing them to be returned to the outlying stations with 105 the least possible loss of time following their original dispatch to the central station. In order to accomplish this important result, the banks of incoming tubes 6 at the central station shown in the drawing are so distrib- 110

uted and arranged that carrier stations 16 may be served directly thereby. In order to bring this about, the incoming tubes 6 are provided at their discharge ends with a 5 swiveled or pivoted carrier directing member 17 which is adapted to be rotated about the axis of the tube to direct carriers either into the chutes 7 and 8 or into delivery tube sections 18 arranged to deliver carriers on 10 tables or desks 19 for treatment by the operators at the stations 16. There is thereby obtained direct delivery of the carriers from the outlying stations to the stations of operators whose duty it is to treat the contents 15 of the carriers. Following the necessary treatment, the carriers are redispached by the operators at stations 16 to the dispatch station 14 by way of tube lines 20 and 21. The carriers thereby are not subjected to 20 treatment by the relay operator nor are they sent to the regular operators' station 10 but are treated directly on their reception at the central station and immediately redispached by the operator at station 5.

25 It will be seen that the emergency or special treatment of carriers thus provided for is especially applicable to the handling of special sales in any one or more departments of a department store in that the service 30 of making change for the departments in question is greatly accelerated, thereby avoiding delays in handling the goods and consequently adding to the number of sales possible to be made in a given time.

35 Following the emergency conditions referred to, the carriers can be again handled in the regular ordinary course by merely rotating the swiveled carrier directing member 17 to its reversed position in which it 40 will deliver to one or another of the troughs or chutes 7 or 8 instead of to the tables 19. The course of the carriers is then by way of the regular operators' station 10, undergoing a relaying or redispaching step in the 45 course of handling as will be clear.

While the provision of the special operators' stations 16 has been referred to as being of an emergency character, these stations, or a portion of them, may be used 50 regularly, as desired, either to supplement the number of operators' stations in use, or to relieve congestion at the relay operators' station 5, or for any other purpose that the circumstances of the work may require.

55 The terms and expressions which I have employed are used as terms of description and not of limitation, and I have no intention, in the use of such terms and expressions, of excluding any mechanical equivalent of the features shown and described, or 60 portions thereof, but recognize that various modifications are possible within the scope of the invention claimed.

What I claim is:—

65 1. In a central station installation for

pneumatic dispatch systems, a relay station at which carriers are received from incoming tubes, operators' stations to which carriers are normally dispached from the relay station, emergency operators' stations, 70 and means for diverting carriers from the relay station and causing the carriers to be delivered directly from the incoming tubes to the emergency stations.

2. In a central station installation for 75 pneumatic dispatch systems, a relay station at which carriers are received from incoming tubes, operators' stations to which carriers are dispached from the relay station in the ordinary course of the work, emergency operators' stations, means for diverting carriers from the relay station and causing the carriers to be delivered directly from the incoming tubes to the emergency stations, and a dispatching station to which 80 carriers are transmitted from the operators' and the emergency operators' stations.

3. In a central station installation for pneumatic dispatch systems, a relay station at which carriers are received from incoming tubes, operators' stations to which carriers are dispached from the relay station in the ordinary course of the work, emergency operators' stations located adjacent to the discharged ends of the incoming tubes, 90 and means associated with the incoming tubes for diverting carriers from the relay station and causing the carriers to be delivered directly to the adjacent emergency operators' stations.

4. In a central station installation for pneumatic dispatch systems, a relay station, a series of incoming tubes, runways leading from the discharge ends of the tubes to the relay station, operator's stations to which carriers are dispached from the relay station in the ordinary course of the work, emergency operators' stations located adjacent to the discharge ends of the incoming tubes, and means associated with the incoming tubes for diverting carriers from the runways and causing the carriers to be delivered directly to the adjacent emergency operator's stations.

5. In a central station installation for 115 pneumatic dispatch systems, a relay station, a series of incoming tubes, inclined chutes leading from the discharge ends of the tubes to the relay station, operators' stations to which carriers are dispached from the relay station in the ordinary course of the work, emergency operators' stations, delivery tube sections leading from the discharge ends of the tubes to the emergency operators' stations, and directing means associated with each incoming tube for causing carriers to be delivered by the tubes either to the chutes or to the emergency operators' stations at the will of the attendant.

6. In a central station installation for pneumatic dispatch systems, a relay station, a series of incoming tubes, inclined chutes leading from the discharge ends of the tubes to the relay station, operators' stations to which carriers are dispatched from the relay station in the ordinary course of the work, emergency operators' stations located adjacent to the discharge ends of the tubes, 5 delivery tube sections leading from the discharge ends of the tubes to the emergency operators' stations; and a carrier directing member mounted on the discharge end of each incoming tube in a swiveled relation thereto, said carrier directing members being capable of adjustment to cause carriers to be delivered either to the chutes leading to the relay station or to the emergency operators' stations as occasion may require.
- 10 7. In a central station installation for pneumatic dispatch systems, a relay station, a series of incoming tubes, inclined chutes leading from the discharge ends of the tubes to the relay station, operators' stations to which carriers are dispatched from the relay station in the ordinary course of the work, a dispatchers' station to which carriers are returned from the operators' stations for redispach to the points of original 15 dispatch, emergency operators' stations located adjacent to the discharge ends of the

tubes, delivery tube sections leading from the discharge ends of the tubes to the emergency operators' stations, a carrier directing member mounted on the discharge 35 end of each incoming tube in a swiveled relation thereto, said carrier directing members being capable of adjustment to cause carriers to be delivered either to the chutes leading to the relay station or to the emergency operators' stations, and tube connections through which carriers may be dispatched from the emergency operators' stations to the dispatchers' station.

20 8. In a central station installation for pneumatic dispatch systems, a relay station and a set of operators' stations to which carriers may be dispatched from the relay station, a set of emergency operators' stations, a series of tubes arranged to deliver 40 carriers alternatively to the relay station or to the emergency operators' stations whereby the installation can be operated entirely by operators in the emergency operators' stations or entirely by a relay operator and 45 operators in the first-mentioned operators' stations.

25 Signed at New York, in the county of New York, and State of New York, this 50 20th day of August, 1926.

55 EDMUND WEIGELE.
